UNITED STATES PATENT OFFICE.

ERTON T. FOLTS, OF CRESWELL, OREGON.

DISPLAY TRAY.

Application filed May 4, 1925. Serial No. 27,775.

My invention relates to display trays of the type adapted to the displaying of articles of merchandise and more particularly those small articles of merchandise that are 5 fairly uniform in size and adapted to being displayed in pyramidal form, or where the same are faced upon the device with the idea of making the display more attractive.

My new and improved display tray 10 is adapted to being pyramided on one or more sides and which may have disposed upon the top of the same a shelf-like structure, adapted to maintain the articles to be displayed upon the apex of the pyramid 15 formed and adapted to maintain thereupon a display card, for the purpose of conveying information upon the articles displayed.

A further object of my invention consists 20 in new and novel features of construction wherein the articles being faced upon the outer surface of the display are held in the formation in which they are placed with preventive means adapted to maintain the faced layers from spreading.

25 A further novelty of my invention resides in the adaptation of the same to tray containers, usually found and employed by merchants and others in the retaining of the articles to be merchandised therein.

30 A further object of my invention consists in so forming the display device that the same may be nested for shipment in small packages, or nested packages, and wherein the same may be assembled at the point of 35 use by those unskilled in manufacturing or assembling operations.

A further object of my invention consists 40 in having the terminal edges and meeting surfaces adapted to retain the faced articles thereupon to prevent their shifting position during the period in which they are in and upon display.

With these and incidental objects in view, 45 the invention consists in certain novel features of construction and combination of parts, the essential elements of which are set forth in the appended claims and to a preferred form of embodiment of which is hereinafter shown with reference to the drawings which accompany and form a part 50 of this specification.

In the drawings:—

Fig. 1 is a perspective view of a tray, wherein one of my three sided display devices has been placed within the tray ready 55 for use.

Fig. 2 is a front elevation of the device shown in Fig. 1, without the articles to be displayed placed thereupon.

Fig. 3 is a cross section view, taken on 60 line 3—3 of Fig. 2, looking in the direction indicated.

Fig. 4 is a front elevation, partially in section of the display device, shown removed from the display tray. 65

Fig. 5 is a plan view of the mechanism shown in Fig. 4.

Fig. 6 is a fragmentary, sectional view, taken on line 6—6 of Fig. 2, looking in the direction indicated, and is made to illustrate 70 how I form the meeting surfaces to facilitate the retention of the faced articles upon the display device.

Fig. 7 is a perspective view of a modified form of my display device, here shown, as 75 possessing only one display surface, combined with the display shelf disposed at the apex of the surface and having a means for maintaining the display card therein.

Fig. 8 is an enlarged front view, partially 80 in section, of the mechanism shown in Fig. 7.

Fig. 9 is a sectional view, taken on line 9—9 of Fig. 8, looking in the direction indicated.

Fig. 10 is a front elevation of the display 85 device shown in Fig. 7, but removed from the display tray.

Fig. 11 is a sectional view, of one preferred form of embodiment of my device, and made more particularly to illustrate one 90 form of attachment of the device to the display tray.

Fig. 12 is a plan view, of a display tray made to illustrate the form of attaching the display device as shown in Fig. 10. 95

Like reference characters refer to like parts throughout the several views.

1 is a display tray of the usual type made of rigid material, having outwardly sloping side walls 2 and 3, and terminating in rolled upper surface edges 4. These display trays 100 are preferably made of rather shallow con-

struction and of substantial area and are adapted to the displaying of confections, fruits and other and various small articles of merchandise and articles of manufacture.

5 In the preferred form of embodiment of my invention, I use a display device, as illustrated in plan view in Fig. 5, wherein I utilize three surfaces 5, 6, and 7, to form a partial frustum of a pyramid, and wherein 10 the device is wider at the base and tapering inwardly from the base, terminating in a shelf-like structure 8, at the top thereof; having upturned edges 9 and 10, adapted to maintain articles to be displayed thereupon and having an upturned rear wall or ledge 11, so arranged that a display card 12, may be inserted in intimate contact with the upturned rear wall 11, and held in placement by the upturned edges 9 and 10. The terminal 15 rear edges of the side walls of the frustum of the pyramid 13 and 14, are turned outwardly in uniform curvature to permit and maintain the articles being faced upon the surface from spreading or otherwise 20 moving from the placed position thereupon. The meeting surfaces of the sides of the pyramid terminating at the point of meeting are formed as shown at 15 in Fig. 6, to prevent the movement of the faced material at these points of contact.

Another preferred form of embodiment 25 of my invention is a single inclined surface 16, and having uniformly curved terminal edges 17 and 18, to prevent the movement of the displayed articles when pyramided upon the surface. A shelf-like top surface 19 may be placed thereupon having upturned edges 20 and 21 and having a rear wall 22 disposed thereupon, with a space between the upturned edges 20 and 21 to permit of a display card 23 being inserted therebetween and being held in position thereby.

Feet 24 and 25, are formed along the 30 lower edges of the stock from which the display devices are made and are adapted to being inserted through a slot 26, within the bottom or side wall of the display tray, and when upturned thereabout, maintain the display device in fixed position in relation with the tray. In Fig. 2, and Fig. 3, I have shown the same as contacting through the front wall of the tray, whereas in Fig. 9, I have shown the same as passing through slots disposed within the bottom surface of the tray and bent as shown at 27 of Fig. 9, the slots being shown at 28 in Fig. 12. However, I do not wish to be limited to any specific manner of attaching the same to the display tray as it is apparent that the same 35 may be attached as shown in Fig. 11, wherein an upturned wall surface 29 may be formed and the foot 30 formed about the upper curled edge of the display tray and held in folded relation therewith, or the same may be placed within the tray when of

the three sided form where the same will remain in an upright position without artificial fastening means.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:—

1. A display tray comprising, a tray container, a display device adapted to the tray by having slits formed on the bottom of the tray, through which feet disposed upon the bottom edge of the display device enter in locking engagement, a rearward inclined face formed by the display device, and curved edges formed upon the terminal edges of the display device adapted to maintain faced articles in position placed thereupon. 80

2. A display tray comprising, a tray container having outwardly sloping side walls, a display device disposed within the display tray and adapted to being maintained in fixed relation with the display tray, the display device having a rearwardly inclined front wall and inwardly inclined side walls with outwardly curving rear terminal edges, a superimposed horizontal shelf with upturned edges and means between the upturned edges adapted to maintain a display card therebetween. 95

3. A display tray comprising a flat bottomed tray having outwardly sloping sidewalls terminating in upper rolled terminal edges, a frustum of a pyramid disposed within the tray and in fixed relation therewith, a horizontal shelf terminal disposed upon the sidewalls of the pyramid, upturned edges at either end of the superimposed shelf, a rear wall, upturned upon the shelf and means disposed between the end walls of the shelf and the upturned rear wall adapted to maintain a display card therebetween. 100

4. A display tray comprising a tray composed of a bottom and outwardly sloping sides, a display device disposed within the display tray, formed of one piece and secured to the display tray in fixed relation therewith, sloping side walls composing the display device having curved terminal edges, a horizontal shelf superimposed above the side walls having upturned edges and means adapted to maintain a display card in upright position upon the horizontal shelf and between the upturned edges. 115

5. A display tray, comprising a tray having outwardly sloping side walls, a display device, having inwardly sloping sides secured to said tray in fixed relationship there- 120

125

130

with, a shelf superimposed thereabove, upturned edges at either end of the superimposed shelf, and means adapted to maintain a display card in upright position thereon.

5 6. A display tray, comprising a flat bottomed tray having outwardly sloping side walls, a display device, having inwardly

sloping face, secured to one end of said tray, in fixed relationship therewith, a shelf superimposed thereabove, upturned edges at either 10 end of the superimposed shelves, and means whereby a display card may be maintained in an upright position thereon.

ERTON T. FOLTS.
